UNITED STATES PATENT OFFICE.

ARTHUR VICTOR BUGLER AND THOMAS EDWARD DELAFONS, OF LONDON, ENGLAND,
ASSIGNORS TO LINOTYPE AND MACHINERY LIMITED, OF LONDON, ENGLAND, A
COMPANY OF GREAT BRITAIN.

SHEET-DELIVERY MECHANISM OF PRINTING MACHINES.

Application filed October 23, 1922. Serial No. 596,289.

To all whom it may concern:

Be it known that we, ARTHUR VICTOR BUGLER and THOMAS EDWARD DELAFONS, both subjects of the King of the United

5 Kingdom of Great Britain and Ireland, and residing at No. 9 Kingsway, London, England, have invented new and useful Improvements in Sheet-Delivery Mechanism of Printing Machines, of which the following is a specification.

10 This invention relates to sheet-delivery mechanism of printing machines in which the grippers for taking the sheets from the impression cylinder or other organ from 15 which those grippers are to receive them, are carried by a plurality of parallel endless chains traversed continuously or intermittently by sprocket or equivalent gearing.

15 In this construction of apparatus, the 20 grippers are secured to gripper shafts extending transversely across the machine from chain to chain and their gripping or vibrating ends are intermittently closed down on to, and opened away from pad 25 shafts extending parallel to the gripper shafts, and between which and the gripper ends the sheets are nipped to convey them from the beforementioned cylinder or organ, and which are afterwards opened from 30 the pad shafts to allow the sheets to drop on to the delivery board.

35 The opening and closing of the grippers may be effected by any convenient means which form no part of the present invention.

40 In this class of mechanism difficulty arises from the stretching and expansion or contraction of the chains, which causes a disturbance in the operative relationship between the chain grippers and the grippers 45 from which they receive the sheets, and in some instances the variation in the lengths of the different chains may be unequal so that the perpendicularity of given sets of chain grippers to the direction of their travel through the machine is correspondingly disturbed.

50 The object of the present invention is to provide means for neutralizing the effects which would ordinarily result from the aforesaid chain variations. For attaining that result we secure the gripper shafts and

pad shafts to the chains in such manner as will admit of them being readily and conveniently adjusted in direction longitudinally of the said chains.

55 The invention will be best understood by reference to the accompanying drawings in which:—

Figure 1 is a diagrammatic side elevation 60 partly broken away, of chain delivery mechanism of the improved construction.

Figures 2 and 3 are views taken at right angles to each other showing in detail, one 65 constructional form of the adjusting devices, Figure 2 being a section taken on a line parallel with the direction of travel of the gripper chains, and

Figures 4 and 5 are views respectively 70 similar to Figures 2 and 3, of a second constructional form of the adjusting devices.

75 Like reference numerals are used to indicate like or corresponding parts in both of the constructional forms illustrated in the drawings.

Referring first to Figure 1, 1 represents 80 in fragmentary form, one of the plurality of parallel endless chains which are traversed continuously or intermittently by sprocket or equivalent gearing represented by the dotted circles 2, 3.

85 As the grippers and gripper pads per se, do not constitute any part of the present invention, they have been omitted from the drawings, but the shafts appertaining to these devices are respectively identified by the numerals 4 and 5, it being further explained that the grippers, which are secured on the shafts 4 in the ordinary manner, are caused to close and open, for gripping and 90 releasing the sheets, by any well-known or convenient means which again form no part of the present invention.

95 In both of the constructional forms represented in the drawings, the gripper shafts 4, and pad shafts 5 (preferably tubular, as shown) are carried in plates 6 which are adjustably secured to brackets 7 forming integral parts of, or rigidly attached to, certain of the links of the chains 1. This adjustable attachment is secured by bolts 8 threaded into the brackets 7 and traversing slots 9 (Figures 2 and 4) formed in the plates 6, so that by releasing these bolts, the

plates 6 together with the respective shafts 4, 5, can be adjusted forwardly or rearwardly on the chains 1, and, by afterwards tightening the bolts, the said parts can be secured in their adjusted positions.

In the arrangement illustrated in Figures 2 and 3, the plate 6 is provided with a rib or series of aligned short ribs 10 in sliding engagement with a groove 11 formed in the juxtaposed bracket 7 so that the proper working relationship of the shafts 4, 5 to the chains 1 will always be maintained, however said shafts be advanced or retired on the chains; this adjustment is effected directly by hand while the bolts 8 are loosened.

The modified construction next to be described differs from that previously described, only in respect of the means for effecting the aforesaid adjustment, the said modification, as represented in Figures 4 and 5, embodying devices for obtaining fine degrees of adjustment and for indicating the extent of such adjustment. To this end, each of the plates 6 has pinned or otherwise rigidly secured to it, a screw 12 which traverses a yoke or fork 13 integral with an arm 14 formed in one with the respective bracket 7, and on this screw are threaded two nuts 15, one on either side of the yoke 13, and, according to the direction in which these nuts are threaded along the screw 12, so will the plate 6 with its shafts 4 and 5, be adjusted forward or backward relatively to the respective chain 1. For indicating the extent of this adjustment, the bracket 7 is provided with a scale 16, and the plate 6 is provided with an index or pointer 17 in registering proximity to the scale; or, obviously the reverse of this arrangement may obtain. These indicating devices serve to show the exact relationship of the different sets of grippers to each other, that is to say, whether they are parallel and at the proper distance apart, and to indicate when any set of grippers is ranged perpendicularly to its direction of travel in the machine.

Having described our invention, we declare that what we claim and desire to secure by Letters Patent is:—

1. In sheet-delivery mechanism for printing machines, the combination with an endless chain and a sheet-gripper shaft carried by said chain, of means whereby said gripper shaft is secured to the chain with a ca-

pacity for adjustment forwardly and backwardly thereon.

2. In sheet-delivery mechanism for printing machines, the combination with an endless chain, and a sheet-gripper shaft and a pad shaft both carried by said chain, of means whereby said gripper shaft and pad shaft are secured to the chain with a capacity for conjoint forward and backward adjustment thereon.

3. In sheet-delivery mechanism for printing machines, the combination with an endless chain of a bracket rigidly connected to the chain, a plate adjustably connected to the bracket with a capacity for adjustment forwardly and backwardly relatively to the chain and a gripper shaft and pad shaft both carried by and adjustable with the said plate.

4. In sheet-delivery mechanism for printing machines, the combination with an endless chain of a bracket rigidly connected to the chain, a plate secured to the bracket and adapted to carry the shafts of the sheet-gripping mechanism, and means adapted to effect adjustment of said plate relatively to the bracket.

5. In sheet-delivery mechanism for printing machines, the combination with an endless chain of a bracket rigidly connected to the chain, a plate secured to the bracket and adapted to carry the shafts of the sheet-gripping mechanism, means adapted to effect adjustment of said plate relatively to the bracket and a device adapted to indicate the extent of such adjustment.

6. In sheet-delivery mechanism for printing machines, the combination with an endless chain of a bracket rigidly connected to the chain, a plate secured to the bracket and adapted to carry the shafts of the sheet-gripping mechanism, a yoke integral with the bracket, a screwed rod fast to the plate and traversing said yoke, two nuts threaded on the rod on respectively opposite sides of the yoke for moving the rod longitudinally, a pointer fast to the plate and a fixed scale on the bracket with which the pointer is adapted to register.

In testimony whereof we have affixed our signatures hereto.

ARTHUR VICTOR BUGLER.
THOMAS EDWARD DELAFONS.
